UNITED STATES PATENT OFFICE.

GEORGE W. MCGILL, OF RIVERDALE-ON-THE-HUDSON, NEW YORK.

WIRE SPRING-CLIP.

No. 818,905.

Specification of Letters Patent.

Patented April 24, 1906.

Application filed September 7, 1905. Serial No. 277,361.

To all whom it may concern:

Be it known that I, GEORGE W. MCGILL, a citizen of the United States, and a resident of Riverdale-on-the-Hudson, in the county of 5 New York and State of New York, have invented certain new and useful Improvements in Wire Spring-Clips, of which the following is a specification.

This invention relates to spring-clips made 10 of wire, having for their object the holding together of loose sheets of paper, prints, and such like material, and provides an improvement therein whereby the resilience or spring of its clamping members when impaired by usage or other causes may be immediately restored by the user without trouble to himself or injury to the clip.

In the accompanying drawings, forming 20 part of this specification, and wherein like letters of reference indicate corresponding parts, there are illustrated some of many ways in which the improvement may be carried into effect, it being understood that the underlying principle thereof common to each 25 may be embodied in other forms of the clip and still be within the scope of the invention, which fundamentally consists in a wire spring-clip having a plurality of clamping members so disposed therein that at the 30 pleasure of the user and without injury to the clip two of such members may alternately be set to bear against either side of a third member with the object of restoring their clamping resilience.

35 In the drawings all six of the figures are views in elevation of forms of the clip, each differing more or less in general configuration, but all having embodied therein the important features herein set forth and having 40 other features common to all.

In the drawings the wire composing the clip is shown folded in manner to provide it with three clamping members, consisting of a central body member A and two wing members 45 B B of equal dimension, disposed one on each side of the body member and having the terminals l l of the wire providing them set in resilient bearing against one side of the lower part of the body member A.

50 In Figure 1 the body member A is provided by folding the composing wire from each end upon a central section of it in manner to provide a T configuration in reverse, the head of the T providing the lower or

transversely-set part of the body member, 55 with the wires providing the T-shank projected centrally above it and folded laterally outward from each other into the two wing members B B, having looped terminals l l set in resilient bearing against one side of the 60 lower or transverse part of the body member A.

The construction of Fig. 2 is practically the same as Fig. 1, the exception being that the terminals of the composing wire instead 65 of being carried up and set within the members B B, as in Fig. 1, are carried up and set outside those members.

Fig. 3 differs in construction from Fig. 1 to the extent of having the body member A 70 folded in triangular formation instead of the reverse T configuration of the latter figure, such open angular formation being more readily provided by machinery than the close T configuration. 75

In Fig. 4 the body member A presents a diamond-like or rhombus configuration and the wing members B B that of the numeral 8.

In Fig. 5 the body member presents a configuration similar to that of Fig. 4, the wing 80 members a polygonal configuration, and their looper-terminals that of rhomboids.

In Fig. 6 the terminals l l of the members B B instead of having loop formation, as in the other figures, are each provided with an 85 open angular formation and are set in the same plane, one angle within the other, and in that position bear against the same side of the member A.

The clip is operated by inserting the material being clipped between the member A and the free ends of the members B B, where it will be held and clamped by the resilience of all the members. 90

When from constant usage the insertion 95 between the clips' clamping members of excessively bulky material or through being subjected to other excessive strain the resilience of these members becomes impaired, it may be readily restored by the user springing 100 laterally the terminals of the members B B around the member A to its opposite side, against which they may remain in spring-bearing, if desired, or be sprung back to the former side with their resilience revived by 105 the movement and which movement may be repeated indefinitely without injury to the clip. In practicing this operation, with the

wing members B B fashioned as shown in Fig. 6; their angular terminals are pressed transversely out of plane with each other and then sprung laterally around the edges of the member A, as in the other forms.

5 The upper looped portions of the wing members B B, provided by the lateral outward folding from the axis of the body member of the wires composing them are, as 10 shown in all the figures of the drawings, provided with areas sufficiently large relatively to admit of this operation being put in practice without straining the normal spring set of the members as a whole or impairing the 15 normal lateral resilient converging of their lower parts. The upward folding of the terminals *l l* of the wing members double the points of bearing between them and the body member and guard the ends of the wire comprising the clip and prevent them from puncturing and defacing the papers or other material entered in the clip and present broad bearing areas or surfaces to coact with corresponding areas of the body member in clamping and holding such material.

Having thus fully described my invention, what I claim as new, and desire to secure by Letters Patent, is—

1. A spring-clip of the character herein described having the wire providing its clamping members so disposed therein that two of such members may alternately be set to bear against either side of a third member.

2. A spring-clip of the character herein described having the wire providing its clamping members so disposed therein that two of such members may be moved laterally around the edges of a third member and set alternately to bear against either side of such 40 third member.

3. A wire spring-clip of the character described having three clamping members so disposed therein that two of them are in constant resilient bearing with the third and are 45 adapted to be moved apart laterally and sprung from one surface of the third member to its opposite surface so as to alternately bear against either of such surfaces, for the purposes herein described.

50 4. A spring-clip of the character described having the wire composing it folded in manner to provide it three clamping members consisting of a central body member extending in part crosswise the clip, and two wing members disposed one on each side of such body member and having their lower terminals set in the same plane and adapted to bear, in that position, against either side of the body member, and be moved from either 55 side of such member to its opposite side.

5. A spring-clip of the character described in which the wire composing it is folded into three unitary clamping members consisting of a transversely-disposed body member and 65 two wing members placed one on each side of

the body member in manner to admit of their lower terminals being alternately moved apart and sprung from one surface of the body member to its opposite surface in alternately bringing the terminals jointly into resilient bearing against one or other of such surfaces.

6. A spring-wire clip of the character described having the wire composing it folded at its central part into a body member transversely disposed therein and having the free end parts of the wire carried outward from such body member in opposite directions and thence downward across its lower part in manner to provide the clip two spring-bearing wing members disposed one on each side of the body member and adapted to bear against it.

7. In a spring-clip of the character described, wherein the wire composing it is 85 folded into three unitary clamping members consisting of a transversely-disposed body member and two wing members placed one on each side of the axis of the body member in manner to admit of their lower terminals 90 being alternately moved apart and sprung from one surface of the body member to its opposite surface in alternately bringing the terminals jointly into resilient bearing against one or other of such surfaces, means admitting of such manipulation of the wing members without straining the normal set of their looped upper parts or impairing the lateral 95 converging resilience of their lower terminals.

8. In a spring-clip of the character described, the upper portions of the wing members B B, provided with areas sufficiently large, relatively, to admit of their lower extremities being moved apart laterally and sprung from one surface of the body member 100 to its opposite surface without straining the normal spring set of such members or impairing the lateral converging resilience of their lower parts.

9. A spring-clip of the character described 110 having the wire composing it folded in a manner to provide three clamping members consisting of a central body member extending in part crosswise the clip with the wires composing it folded outward in the same 115 plane from the axis of the clip and merging into two wing members disposed one on each side of such axis, with the wires providing them converging downwardly and having their terminals folded back upwardly and set 120 in spring-bearing with one side of the body member.

10. A spring-clip of the character described having the wire composing it folded in a manner to provide three clamping members consisting of a central body member extending in part crosswise the clip with the wire composing it folded outward laterally from the axis of the clip, and in the same 125 plane, and merging into two dependent wing 130

members of equal dimensions set adjacent to each other and bearing against the body member at a plurality of its crossings, and having the terminals of the wires carried back upwardly and in the same plane across the body member and in spring-bearing with it.

Signed at Riverdale-on-the-Hudson, in the county of New York and State of New York, this 24th day of August, A. D. 1905.
